United States Patent Office.

CHARLES H. ECCLESTON, OF OXFORD, NEW YORK.

Design No. 4,470, dated November 15, 1870.

DESIGN FOR THE FACE-PLATE OF A SASH-LOCK.

The Schedule referred to in these Letters Patent and making part of the same.

To all whom it may concern:

Be it known that I, CHARLES H. ECCLESTON, of Oxford, in the county of Chenango and State of New York, have invented and produced a new and original Design for a Face-Plate of a Window-Sash Lock, of which the following is a specification.

The nature of my design is fully represented in the accompanying drawing, to which reference is made.

I claim as my invention—

The design for a face-plate of a window-fastener, as shown in the drawing.

In testimony that I claim the above, I have hereunto subscribed my name in the presence of two witnesses.

CHAS. H. ECCLESTON.
